SUSPENDER LOOP FASTENER

Daniel I. Reiter, New York, N. Y.

Application February 11, 1938, Serial No. 189,920

5 Claims. (Cl. 85—40)

This invention relates to inseparable two-piece fasteners and particularly to the type wherein the fastener parts are assembled and permanently locked together by relative axial compression.

5 My invention is particularly adapted for use in fastening back the end part of a suspender strap, where the suspender strap is bent over the loop carrying the strap to form a looped end on the strap slideable on the loop. Heretofore, tubular rivets have been used for this purpose, but such rivets when bent over and clenched, present comparatively sharp elements on the inside of the strap, which elements tend to rub against or catch in the shirt of the wearer and to ultimately tear the shirt or to prick the wearer.

10 My invention therefore contemplates the provision of a two-piece quick-attachable fastener, each piece being provided with a flange adapted to engage either the surface of the body portion 20 of the suspender strap or the bent-over or folded portion thereof, the fastener parts or pieces being so constructed that they are easy to assemble, economical to manufacture and efficient in operation, and being permanently assembled by merely compressing the parts toward each other after the passage thereof in opposite directions through the strap parts to be fastened.

15 My invention further contemplates the provision of a fastener of the character mentioned which can be economically and efficiently produced by automatic machinery and hence which is sufficiently inexpensive to take the place of rivets without the disadvantages of rivets hereinbefore mentioned.

20 The various objects of the invention will be clear from the description which follows, and from the drawing, in which,

25 Fig. 1 is a fragmentary side elevation of an end-folded suspender strap and the carrying loop therefor partly in section, showing my improved fastener as it appears fastened in its operative position securing the folded part of the strap in place.

30 Fig. 2 is a combined partial elevation and a partial vertical section of my improved fastener, showing the parts partly assembled but prior to the complete assembly thereof.

35 Fig. 3 is a similar view of a slightly modified form of the same.

40 In the practical embodiment of my invention which I have shown by way of example, the end portion 10 of the suspender strap 11 is bent back around the strap-supporting loop 12 on to the body of the strap to form the slide loop 13, in the usual manner. To secure said end portion 10 to

the body portion of the strap, I provide the two-piece inseparable fastener comprising the inter-engaging and cooperating anvil part 14 and the eyelet part 20, each of said parts being made of a single piece of suitable metal, and each being passed through at least one of the layers of strap material by piercing the material or passing through suitable openings in said layers.

45 The anvil part 14 consists of an enlarged head or flange 15 having a preferably convex outer surface 16 and a preferably flat under surface 17 adapted to contact with and to be pressed slightly into or to otherwise engage the surface 18 of the strap body. Depending from the head or flange 15 and of less outer diameter than that of said 50 flange, is the hollow cylindrical extension or wall 19 which is provided with the opening 23 at its bottom and with the concave surface 21 at the interior of the top thereof, which surface forms the effective anvil portion of said part 14. As shown 55 in Figs. 1 and 2, the cylindrical wall 19 is curved inwardly at its lower end as 22 to make the opening 23 of less diameter than the remaining uniform inner diameter of the wall 19. Evidently, the anvil part 14 is most conveniently made from 60 solid rod stock by suitable automatic machinery, the free end portion of the wall 19 being rolled inwardly.

65 The eyelet part 20 is preferably made of a single piece of thin sheet metal and consists of the flange 24 which is adapted to engage the innermost surface 25 of the strap part 10 and the projecting eyelet portion 26 which is preferably open at its top 27 and its bottom and which tapers slightly 70 inwardly toward said top. It will be understood 75 that the eyelet part 26 is collapsible under compressive stress thereon, as is shown for example in Fig. 1.

80 The parts are assembled by inserting the wall 19 through the opening 28 of the strap body 11, 85 inserting the eyelet part 26 of the eyelet 20 through the opening 29 of the strap part 25 and through the opening 23 into the interior of the wall 19. The parts are then axially compressed 90 together so that the top 27 of the eyelet part engages the concave anvil surface 21, whereafter on further axial compression of the parts together, said eyelet part 26 is compressed to such an extent 95 that it collapses within the hollow wall 19 and shortens in over-all length. During the collapse 50 of the eyelet part 26, said part spreads or expands at certain parts to a diameter greater than the diameter of the opening 23, whereby the parts 14 and 20 are permanently secured together against separation. Since the upper part of the eyelet 55

is slightly smaller than the lower part thereof and consequently somewhat weaker, it is the upper part of the eyelet which collapses. During the compression of the parts together, it will be understood that the flange 24 engages the surface 25 of the strap part and provides a flat or slightly rounded surface at said flange free of any protuberances or any sharp edges which might tend to tear the article of clothing against which said flange may rub. The head surface 17 also engages the strap surface 18 at this time, such engagement of the head and flange with the strap surfaces determining the extent of the relative axial compressive movement of the fastener parts.

15 It will be seen from the above description that I have provided a simple, inexpensive but efficient inseparable fastener to secure two sheets or layers of material together by means of a simple and easily applied axial force, and that 20 the oppositely disposed flanges of the thus assembled fastener provide smooth surfaces avoiding all danger of tearing or otherwise injuring an article of clothing with which they come in contact.

25 While I have shown and described a certain specific embodiment of my invention, I do not wish to be understood as limiting myself thereto, but intend to claim the invention as broadly as may be permitted by the state of the prior art 30 and the scope of the appended claims.

I claim:

1. A two-piece inseparable fastener for use in securing together the two thicknesses of material of a suspender strap, which strap is folded back on itself to provide a loop at an end of the strap and to provide two thicknesses of strap material beyond the loop, each of said thicknesses having a cylindrical opening therein aligned with the opening of the other thickness, 40 one piece of said fastener constituting an anvil part being formed from solid stock and having a solid head of sufficient thickness to withstand the distorting effect of the eyelet hereinafter mentioned without the aid of a head-supporting 45 tool, the outer surface of said head being flush with the outer surface of one thickness, a hollow cylindrical portion depending from the head inwardly of the periphery thereof, the length of said cylindrical portion being slightly greater 50 than the thickness of said one thickness of material, said cylindrical portion being of substantially the same diameter and shape throughout as, and closely fitting, the cylindrical wall of said opening in said one thickness except at the bottom 55 part of said cylindrical portion, said bottom part projecting beyond said one thickness and into the opening of the other thickness and being rolled inwardly toward the axis of said cylindrical portion and being of gradually diminishing 60 diameter, least at its extremity to form an opening at said extremity of less diameter than the remaining internal diameter of the cylindrical portion, the internal diameter being the same throughout the cylindrical portion except 65 at said extremity, the other piece of said fastener consisting of a flanged hollow eyelet passing through the other thickness of material and into the cylindrical portion, the upper end part of said eyelet being distorted in an indeterminate 70 manner to an irregular diameter greater than that of the opening but not greater than said internal diameter of said cylindrical portion.

2. A two piece inseparable fastener adapted to be inserted in opposite directions into a pair of aligned cylindrical openings in two layers of ma-

terial to hold said layers together, said fastener comprising a one-piece anvil part of solid rod stock formed with a substantially flat disc-like solid head of substantial thickness sufficient to insure collapse of the eyelet hereinafter mentioned without distortion of said head and without the aid of a head-supporting tool, said anvil being formed with a hollow cylindrical extension depending from the head inwardly of the periphery of the head, the outermost surface of said head 10 being flush with the adjacent surface of one of said layers when the fastener is assembled with said layers, said extension being of sufficient length to pass through one of said openings and to enter but not to pass through the other opening, 15 a concave surface at the interior of the top of the extension closing the upper end of said extension, said concave surface meeting the internal cylindrical surface of the extension at a point spaced substantially below said head, said 20 extension being of uniform inner diameter and of uniform outer diameter except at the lower end thereof to engage the cylindrical wall of the opening in one of said layers, said lower end gradually diminishing in diameter to an opening 25 at the extreme bottom of said extension to provide a concave inner lower surface on said extension above the opening and a convex smooth outer surface thereon, the diameter of the opening being less than the remaining internal diameter 30 of the extension, the thickness of said extension being less than the thickness of said head, and a one-piece eyelet part adapted to pass through into the other opening of said layers of material and into engagement with the concave 35 surface of the top of the extension, said parts, when compressed together with the eyelet inserted into said extension, being permanently secured together by the collapse of the upper portion of the eyelet part in an indeterminate manner and the enlargement of said upper portion to an effective irregular diameter greater than the diameter of the bottom opening of the extension.

3. In a suspender loop strap doubled on itself 45 to form two layers of material each having a cylindrical opening therein of substantially uniform diameter, means entering the openings to secure said layers together comprising a hollow rivet having a solid head at one end and a hollow 50 cylindrical extension of substantially uniform diameter depending from the head and open and rolled concavely inwardly at the other end of the rivet to a diameter less than the internal diameter of the remainder of the extension, said extension closely fitting the wall of the opening in one of the layers of material, and a flanged eyelet passing through the opening of the other layer and irregularly spread inside of the extension to an irregular diameter greater than the least diameter of the rolled end of the extension.

4. A two-piece inseparable fastener comprising an anvil part of a single piece of material having a substantially flat head provided with an annular plane exposed under surface, a concave central under surface partly above and partly below the plane surface and a convex outer surface, said head being of solid material between said surfaces and being of sufficient thickness to withstand by itself the distorting effect 65 of the eyelet part hereinafter mentioned when said eyelet is forced against said concave surface and an integral hollow cylindrical extension projecting from the inner periphery of said plane surface and closed at its top by said concave sur- 70 75

face and of less outer diameter than that of the head, said extension having an inner lateral surface of uniform diameter except at its bottom part, said bottom part gradually diminishing in diameter and being of lesser diameter than that of the remainder of said lateral surface, said lateral surface terminating at its top in said concave surface, and a flanged eyelet part having a projecting eyelet portion adapted to be forced into engagement with said concave surface and spread to an effective irregular diameter greater than the interior diameter of said bottom part but not greater than that of said lateral surface.

5. In a fastener of the character described, an anvil part in the form of a one-piece hollow rivet of uniform diameter open at its bottom and having a solid head at its top, a hollow externally

and internally cylindrical extension depending from and of less diameter than said head, an inwardly concave and outwardly convex bend at the bottom part of the extension gradually diminishing in diameter and reducing the internal 5 diameter of the rivet at its bottom extremity to an amount less than that of the remainder of the extension, and a flanged eyelet part adapted to be forced into the interior of the anvil part and distorted therewithin in an indeterminate 10 manner above said reduced bottom and below the top to increase the effective diameter of said eyelet part, said solid head at the top of said anvil part being of sufficient thickness to withstand unaided the distorting effect thereon of said eye- 15 let part.

DANIEL I. REITER.
